UNITED STATES PATENT OFFICE.

RICHARD HAWKE ROGERS, OF LONDON, ENGLAND.

WHEEL OR PULLEY.

1,346,511.

Specification of Letters Patent.

Patented July 13, 1920.

Application filed April 23, 1918. Serial No. 230,365.

To all whom it may concern:

Be it known that I, RICHARD HAWKE ROGERS, a subject of the King of England, residing at London, England, have invented 5 certain new and useful Improvements in Wheels or Pulleys, of which the following is a specification.

This invention relates to cheap and light wheels or pulleys and a process of making 10 the same from sheet material, for instance from pressed sheet-steel.

The principal object of the present invention is to make end-plates for the pulleys available without alteration to be used in 15 combination with more than one diameter of cylindrical body for the wheel.

A method of making wheels and pulleys according to the present invention comprises the following steps:—End-disks are 20 formed by making pairs of similar plates with central and, if desired, other holes in one or both plates, bending or stamping on each plate an upstanding annular corrugation both of the same form and dimensions, 25 then taking a strip or ribbon of appropriate length and width and of a flat or channeled or other form in cross-section as may be desired according as the pulley-barrel is to be grooved or not or cambered or otherwise 30 formed, and bending it into the form of a cylinder of the desired diameter; next the corrugated end-plates are placed against the respective ends of that cylinder so that (according to the diameter chosen for the 35 cylinder) the margin of the two cylinder-ends shall be received in the cavities of the respective annular corrugations when the cavities are presented toward them, or alternatively shall be received upon the outer 40 shoulders or against the inner shoulders of the annular corrugations when the plates are so faced that the cavities face away from the cylinder-ends. Any pair of such end-plates with a single corrugation on each is 45 thus available without alteration to receive either a cylinder which has a diameter equal to that of the annulus constituted by the corrugation cavity, or one which has a diameter a little larger, and equaling that of 50 the annulus constituted by the outer shoulder of the same corrugation, or a little smaller and equaling that of the annulus constituted by the inner shoulder of the same corrugation.

55 In the foregoing description of the

method, end-plates suitable to three different diameters of cylinder are described for the sake of simplicity, but the present invention comprises also an amplification of the same method which consists in making 60 on each end-plate a plurality of annular corrugations concentric with one another with the summits of the corrugations directed in opposite directions from opposite sides of the same plate. Preferably these corruga- 65 tions are “waved” in cross-section in such a manner that the summit of a wave on one face of a plate corresponds with the hollow 70 between two waves which project on the opposite face. With four summits on one side 70 of the plate and three summits on the other, a pair of plates can be used to accommodate nine different diameters of cylinder; hence it will be seen that a simultaneous manufacture of end-plates all of one sort will serve 75 for a multiplicity of different sizes of cylinders. The method is equally applicable should coned pulleys be required, in which case the body of the pulley instead of being a cylinder, will be made by folding in a 80 manner well understood a flat arc of sheet metal into conical form and engaging a smaller end of the hollow cone with the corrugation of one end-plate and the larger end with the corrugation of the other end-plate. 85

In the accompanying drawings:—

Figure 1 is a side elevation of a pulley constructed according to the present invention, in place on a shaft;

Fig. 2 is a vertical central section on the 90 line 2—2 in Fig. 1;

Fig. 3 is a view similar to Fig. 1 with an alternative form of pulley-boss and an alternative arrangement of the end-plates of the pulley;

Fig. 4 is a section on the line 4—4 of Fig. 3;

Fig. 5 is a view similar to Fig. 2 but with a coned instead of a cylindrical barrel for the pulley;

Fig. 6 is a flat arc of sheet-metal before it is bent into the cone seen in place in Fig. 5;

Fig. 7 is a side elevation of a cylindrical pulley having end-plates in each of which 105 there is a multiplicity of grooves;

Fig. 8 is a section on the line 8—8 in Fig. 7;

Fig. 8^a is a view of a flat strip of sheet-metal which is bent into circular form and 110

forms the barrel of the pulley shown in Figs. 7 and 8; and

Fig. 9 is a view similar to Fig. 8 wherein the same end-plates as are seen in Fig. 8 are combined with a channeled circular strip, which latter forms a grooved body for the pulley.

Fig. 10 is a view similar to Fig. 7 except that in Fig. 10 a triangular plate for keeping the nuts from turning is employed as hereinafter described.

Like reference-letters indicate like parts throughout the drawings.

In the pulley shown in Figs. 1 and 2 the 15 end-plates E are identical with one another and they hold in the corrugations c on each plate the ends of the cylinder C of sheet-metal which forms the body of the pulley.

In the pulley shown in Figs. 3 and 4 the 20 end-plates E which are identical with one another, have the summits of their corrugations c directed toward one another so that they can engage the opposite ends of either a cylinder C resting upon the outer shoulders of the corrugations c, or of a cylinder C¹ which is shown in chain-lines as resting 25 upon the inner shoulders of the same corrugations.

In the pulley shown in Fig. 5 there are 30 two end-plates E identical with one another and having identical corrugations c on each plate, the summits of the corrugations being directed both in the same direction and a coned barrel K being engaged at one end 35 in the recess of one corrugation, and at the other end upon the outer shoulder of the corrugation in the other plate. The flat strip to form the cone is shown separately in Fig. 6.

40 In the pulley illustrated in Figs. 7 and 8 there are two end-plates identical with one another in all respects; as shown, the corrugations accommodate the ends of a strip shown flat in Fig. 8^a and bent into a cylinder C in Fig. 8. Nine different diameters of cylinder could be accommodated between two end-plates such as are shown in Fig. 8.

45 In the pulley shown in Fig. 9 there is a channeled strip, bent into a cylinder C in which the channel provides a groove g, say for a band.

A cone K is shown in Fig. 9 in chain-lines to indicate the manner in which the 50 same two end-plates E, E of Fig. 9 could form part of a cone pulley. Various dimensions of cone could be accommodated between the two end-plates E, E of Fig. 8 or of Fig. 9, instead of various diameters of cylinder.

55 A boss B, Figs. 2, 5, 8 or 9 can be placed in the interior of the cylinder or cone before the end-plates E are put on, and it serves as a distance-piece for them. This boss may have a central bore and projecting end-rings r, the latter to center a con-

tiguous end-plate by entering the correspondingly dimensioned hole therein. Bolts b or rivets parallel with the axis of the pulley may be passed through the end-plates E and the boss B to hold them all 70 together; the holes for these bolts may be made in the end-plates E when the corrugations are stamped. Instead of making holes in the boss for the bolts, slots s may be made in the exterior of the boss in which 75 the shanks of the bolts will lie, and the body of the boss between these exterior slots instead of being left cylindrical, as in Figs. 1 and 7, may be cut away so that the boss assumes the triangular form, as 80 illustrated by the boss B¹ in Figs. 3 and 4, lighter than the cylindrical form. If preferred the central hole in each end-plate E may be made as large as is indicated by chain-lines in Fig. 3 and there should then be three semi-circular recesses at 1, 2 and 3 in the periphery of the hole, arranged to engage the bolts lying in the three slots in the boss B¹ so as to afford driving connection between the boss and the plates. 90

The boss may have the usual key-way in it, or may have a radial hole for a grub-screw GS to hold it on the shaft. A hole H may be made in the cylindrical portion of the pulley to enable access to be had to 95 this screw.

The ends of the ribbon or sheet forming the pulley-body where they meet one another may have lateral tabs T to engage in slots S formed in the end-plates which will 100 keep it from unwinding, or they may be internally butt-strapped and riveted or they may be sweated together or otherwise secured to one another as may be desired.

In Figs. 8 and 9, spring washers sw are 105 shown, which keep the nuts on the bolts b from turning; but they might be kept from turning by any other convenient means, for instance by the bent-up tips t of a flat triangular plate TP through which plate the 110 bolts b pass, as shown in Fig. 10.

What I claim as my invention and desire to secure by Letters Patent is:—

1. A pulley comprising similar end-disks, each disk having waved annular corrugations on both faces of the plate and being provided with tab-receiving slots, and a strip of rigid sheet material with lateral tabs bent into tubular form with the opposite ends of the tube clamped between the faces 120 of the disks and engaged by the corrugations thereof and with the lateral tabs engaged in the tab-receiving slots. 115

2. A pulley comprising similar end-disks, which are provided each with a waved annular corrugation and are arranged with the summits of the corrugations directed toward one another, and a coned tubular member clamped between the faces of the disks and seated upon the corrugation thereof. 125

3. A pulley comprising similar end-disks, which are provided each with a plurality of waved annular corrugations and are arranged with the summits of the corrugations directed toward one another, and a coned tubular member clamped between the faces of the disks and seated at one end upon a corrugation of smaller diameter of the one disk and at the other end upon a corrugation of larger diameter of the other disk. 5
4. A pulley comprising similar end-disks, which are provided each with a waved annular corrugation and a tab-receiving slot and are arranged with the summits of the corrugations directed toward one another, and a tubular member having a tab at each end thereof clamped between the faces of the disks and seated upon the corrugations thereof and with the tabs engaged each in a tab-receiving slot. 10
5. A pulley comprising similar end-disks, whereof each disk has an annular corrugation, and a tab-receiving slot, and a strip of rigid sheet material with lateral tabs bent 15 into the form of a tubular member with the opposite ends of the tubular member clamped between the faces of the disks and supported by the corrugations thereof and with the lateral tabs engaged each in a tab-receiving slot. 20
6. A pulley comprising similar end disks, each disk having an annular corrugation, and an arcuate strip of rigid sheet material 25 bent into coned tubular form with the opposite ends of the tube clamped between the faces of the disks and engaged in the corrugation of one disk and seated on the corrugation of the other disk. 30
7. A pulley comprising similar end disks, whereof each disk has an annular corrugation and is provided with tab-receiving slots at various distances from the center thereof, and an arcuate strip of rigid sheet material with lateral tabs bent into coned tubular form with the opposite ends of the tube 35 clamped between the faces of the disks and supported by the corrugations thereof and with the lateral tabs engaged each in a tab-receiving slot. 40
8. A pulley comprising similar end-disks, whereof each disk has an annular corrugation and is provided with tab-receiving slots at various distances from the center thereof, and an arcuate strip of rigid sheet material with lateral tabs bent into coned tubular 45 form with the opposite ends of the tube clamped between the faces of the disks and engaged in the corrugation of one disk and seated on the corrugation of the other disk and with the lateral tabs engaged each in a tab-receiving slot. 50
